METHOD FOR ADJUSTING THE LENGTH OF STRUCTURAL MEMBERS

Filed Dec. 23, 1931

UNITED STATES PATENT OFFICE

2,029,121

METHOD FOR ADJUSTING THE LENGTH OF STRUCTURAL MEMBERS

Robert Seeman, Merrick, N. Y., and Allen R. Wilson, Philadelphia, Pa., assignors to Ernest H. Pacy, Pittsburgh, Pa.

Application December 23, 1931, Serial No. 582,840

13 Claims. (Cl. 29—151)

Our invention relates to the adjusting of the length of structural members, and is particularly useful for adjusting the length of the eye-bars for bridges, although it has numerous other applications.

In certain structures it sometimes becomes desirable to adjust the length of certain of the structural members. For instance, many bridges employ eye-bar members in their construction.

These eye-bars have eyes at each end, which eyes are engaged by pins. After a period of time, the eye-bars become loose and rattle, due to wear on the edges of the bar or on the pins passing through these eyes, or due to an increase in the length of the members, or to a combination of these causes. Due to the fact that the members do not wear evenly, some members are increased in length, which throws too large a proportion of the strain on certain members, and as a consequence, the bridge as a whole is weakened. The strength of the structure can be increased and its life materially lengthened if this wear can be taken up. Occasionally it is necessary to increase the length of these eye-bars, and sometimes it is necessary to replace one.

It has heretofore been customary to construct devices of the general nature herein contemplated, in such manner that the device has to be left in position on the structural member when the repair is completed. This is both unsightly and expensive, particularly in a structure where several of its members have been adjusted by the method disclosed, for instance, in U. S. Patent No. 1,714,187, granted May 21, 1929, to Ernest H. Pacy, and over which the present invention is an improvement.

According to our invention, we provide a method for adjusting or changing the length of structural members, whereby such means can be used over and over again for this purpose. It is particularly useful for taking up slack in the eye-bars of bridges. It can also be used in operations in which the length of such eye-bars is to be increased, and it has numerous other applications.

This invention contemplates the use of a take-up device or an adjustable connector utilizing a screw-thread adjustment which can be removably connected at spaced points to the structural members, the length of which it is desired to adjust or change. In practice, shoulder plates are connected to the members, preferably by welding. The take-up device is removably connected to such shoulder plates and the threaded members tightened so as to test the connections.

The eye-bar may then be severed as by a cutting torch, and the overall length of the bar adjusted by means of the threaded members. The severed portions of the eye-bar are then fastened together by splice plates which are secured in position, preferably by welding. The take-up device may then be removed.

In the accompanying drawing, we have shown for purposes of illustration only, one form of apparatus suitable for carrying out the invention, in which

Figure 1 is a side elevation showing the method of practicing the invention with the take-up device in position on the structural element to be adjusted, the drawing showing the parts after the adjusting operation has been completed;

Figure 2 is a section taken on the line II—II of Figure 1, looking in the direction of the arrows;

Figure 3 is a longitudinal center line section of the adjusted eye-bar after the take-up device has been removed;

Figure 4 is a transverse section on the line IV—IV of Figure 3; and

Figure 5 is a transverse section taken on the line V—V of Figure 1, looking in the direction of the arrows, with the take-up device in position.

In practicing our invention, we provide a device which may be secured to the structural element, the length of which is to be adjusted, after which the structural element is severed at a point intermediate the length of said device, said device then taking the tension. The device which we have shown for this purpose comprises two sets of plates, one set being designated 2 and the other set being designated 3. The two plates of each set are provided with registering holes through which bolts 4 are passed, these bolts being provided with nuts so that the plates can be clamped onto the structural member 5 which is to be repaired. Inserted between the plates 2 are the flattened end portions 6 of rods 7 having threaded portions 8. Similar rods 9 with flattened end portions 10 and threaded portions 11 are bolted to the plates 3. The threaded portions 8 and 11 of these rods are reversely threaded and are engaged by a turnbuckle 12.

In the use of this device, the point is first selected along the length of the eye-bar at which the repair is to be made. Shoulder plates or buttresses 13 are first welded onto both faces of the eye-bar some distance from the point where the eye-bar is to be severed. These plates are preferably bifurcated as shown in order that

the length of the edge weld can be increased. The two pairs of plates are then clamped to the eye-bar, the plates being preferably notched at 2a and 3a for engagement with this shoulder. 5 The adjustable connectors comprising the turnbuckle 12 and the two threaded rod members 7 and 9 are then adjusted to length and are bolted to their respective plates. After the take-up device comprising the wing plates and the adjustable rods, has been thus secured to the eye-bar, it is severed at 14. If the eye-bar is too long, or it is desired to shorten it to take up for wear at its ends, a definite length of metal is removed at the point 14, whereas if it is desired to 10 lengthen the eye-bar, a single cut at this point is made. After the cutting has been completed, the turnbuckles are operated either to draw the severed ends toward each other or to let them move apart to the necessary extent, depending 15 on whether the operation is one of shortening or lengthening the bar. After the proper adjustment has been made, splice plates 15 are welded to the opposite faces of the severed ends of the bar. These splice plates also preferably have bifurcated end portions in order to increase the 20 length of the edge weld. The splice plates having been secured in place, the take-up device may then be removed. In removing them, the turnbuckles are preferably slackened off gradually 25 in order that the strain will be gradually applied to the splice plates so that if there is any weakness in the splice it may be detected before the take-up device has been completely removed. In operating in this way, the same take-up device 30 can be used over and over again.

It may frequently happen that the eye-bars are of greater thickness than the width of the flattened terminal portions of the threaded rod members. In case the eye-bars 5 are thicker 40 than the flattened end portions 6 and 10 of the threaded rod members, shims 16 should be inserted between the flattened ends and the wing plates 2 and 3, as shown in Figure 5. After the splicing of the ends has been completed, the 45 joint comprises merely the two splice plates connecting the adjacent ends of the bar, as shown in Figures 3 and 4. The shoulder plates 13 remain in position on the bar and are available for use in the event that any further adjustment 50 should ever be required.

It will be appreciated that the invention may be used in a like manner for joining the ends of any two structural members, particularly when such members are placed in a structure where 55 they are under tension.

The method provides a convenient and satisfactory process for adjusting the length of the structural members, or joining the ends of two structural members. It has a considerable advantage over methods as heretofore practiced wherein the take-up device, which is necessarily heavy and expensive, must remain as a permanent, integral part of the structure, these take-up devices being unsightly as well as expensive.

It will be understood that we have illustrated and described in detail a preferred embodiment of the take-up device and the manner of using it, but various changes and modifications may be made therein within the scope of the appended 70 claims.

We claim:

1. The method of adjusting the length of a structural member, which comprises applying a removable take-up device to the member at spaced points thereon, tightening the take-up

device to put it under strain to test it, thereafter severing the structural member in the portion spanned by the take-up device, adjusting the severed ends with respect to each other, joining the severed ends, and removing the take-up 5 device from the member.

2. The method of adjusting the length of a structural member, which comprises fastening shoulder plates thereto at spaced points, applying a removable take-up device to the member to cooperate with the shoulder plates, tightening the take-up device so as to test the shoulder plates, severing the structural member between the connections, adjusting the severed ends with respect to each other, applying splice plates to 15 the severed ends to joint them, and removing the take-up device from the member.

3. The method of adjusting the length of a structural member, which comprises fastening shoulder plates to the member as spaced points, 20 applying a removable take-up device to the shoulder plates, tightening the take-up device so as to test the welds, severing the structural member between the shoulder plates, welding a splice plate to the severed ends to join them, and re- 25 moving the take-up device from the member.

4. The method of adjusting the length of a structural member, which comprises fastening shoulder plates to the member at spaced points, 30 applying a removable take-up device to the shoulder plates, tightening the take-up device so as to test the welds, severing the structural member between the shoulder plates, adjusting the severed ends with respect to each other, welding a splice plate with bifurcated ends to the severed 35 portions and on each side thereof, and removing the take-up device from the member.

5. The method of adjusting the length of a structural member, which comprises applying a removable take-up device to the member at 40 spaced points thereon, severing the structural member between the spaced points, adjusting the severed ends with respect to each other, joining the severed ends and removing the take-up device from the member.

6. The method of adjusting the length of structural members, which comprises fastening shoulder plates thereto at spaced points thereon, applying wing plates adapted to cooperate with and bear against the ends of the shoulder plates, 50 connecting the wing plates by means of adjusting members, and thereafter varying the length of the adjusting members to move the parts to which the shoulder plates are attached toward or away from each other.

7. The method of adjusting the length of a structural member, which comprises welding shoulder plates to the member on opposite sides thereof and at spaced points thereon, removably connecting a take-up device to cooperate with 60 and bear against the shoulder plates, severing the structural member between the shoulder plates, adjusting the severed ends with respect to each other, joining the severed ends and removing the take-up device from the member.

8. The method of adjusting the length of a structural member, which comprises welding shoulder plates to the member at spaced points thereon, removably connecting a take-up device to cooperate with the shoulder plates, severing 70 the structural member between the shoulder plates, adjusting the severed ends with respect to each other, applying splice plates to join the severed ends of said member, and removing the take-up device from the member.

9. The method of adjusting the length of a structural member, which comprises welding shoulder plates with one end bifurcated to the member at spaced points thereon, removably connecting a take-up device to cooperate with the shoulder plates, severing the structural member between the shoulder plates, adjusting the severed ends with respect to each other, applying splice plates with bifurcated ends on each side of the structural member to join the severed ends of said member, and removing the take-up device from the member.

10. The method of adjusting the length of a structural member in the structure, which comprises forming buttresses thereon at spaced points in the length of said member, applying an adjustable connector to said member in such manner as to cooperate with the buttresses, taking up on said connector to exert a strain on the buttresses to test the security thereof, severing the structural member between the buttresses, adjusting the severed ends with respect to each other, and thereafter joining the ends and removing the adjustable connector.

11. The method of adjusting the length of a structural member in the structure, which comprises forming buttresses thereon at spaced points in the length of said member, applying an adjustable connector to said member in such

manner as to cooperate with the buttresses, severing the structural member between the buttresses, adjusting the severed ends with respect to each other, and thereafter joining the ends and removing the adjustable connector. 5

12. A method of the class described, comprising the formation of buttresses on a structural element at each side of a point where said element is to have a joint, applying an adjustable connector to said element in such manner as to bear against the buttresses thereon, adjusting said connector to bring the portions of said element to be joined into the desired relation, forming a joint between such portions, and removing the adjustable connector. 10

13. A method of the class described, comprising welding shoulder plates on a structural member to form buttresses at each side of a point where said member is to have a joint, applying an adjustable connector to said element in such manner as to bear against the buttresses thereon, adjusting said connector to bring the portions of said element to be joined into the desired relation, applying splice plates to the two portions of said element to join them, and removing 20 25 the adjustable connector.
